(57) **CLAIM**

I claim the ornamental design for a wearable ring, as shown and described.

DESCRIPTION

FIG. 1 is a front, perspective view of a wearable ring showing my new design according to a first embodiment; FIG. 2 is a top view thereof;

FIG. 3 is a front view thereof, the back view being a mirror image thereof;

FIG. 4 is a right side view thereof, the left side being a mirror image thereof;

FIG. 5 is a bottom view thereof;

FIG. 6 is a front, perspective view of a wearable ring showing my new design according to a second embodiment; FIG. 7 is a top view thereof;

FIG. 8 is a front view thereof, the back view being a mirror image thereof;

FIG. 9 is a right side view thereof, the left side being a mirror image thereof; and,

FIG. 10 is a bottom view thereof.

1 Claim, 2 Drawing Sheets
